TELEPHONE INSTALLATION

Martin Hebel, Hechendorf-on-the-Pilsensee,
Upper Bavaria, GermanyApplication September 15, 1937, Serial No. 163,941
In Germany October 17, 1936

6 Claims. (Cl. 179—27)

This invention relates to telephone installations and to the provision of a supervisory station in installations in which the selectors are set directly by the subscribers, that is to say, without the assistance of storing or translating devices. It is known to provide installations having storing and translating devices with supervisory devices which are operated in accordance with the setting and the condition of the storing selector so as to indicate such things as the failure to begin a conversation, failure to commence or to terminate a connection and which switch the caller over to an operator. It is, however, not easy to provide such supervision in installations in which the selectors are set direct by impulses sent out when the calling subscriber dials because there is no member such as a storing device available which is common to all the selectors used in making the connection. In such installations, it is usual merely to indicate the state of operation of the various selectors in the selector racks. Another scheme is to connect a few subscribers to a supervisory station in which the connections made to and from these subscribers are watched and from which the subscribers are notified where need be.

The invention enables the supervision of all connections to be effected simply and thoroughly.

In accordance with the invention, switch means are provided which are dependent upon the receipt of selecting current impulses, further switch means are provided which are dependent upon the called subscriber's line being tested and further switch means are provided which are dependent upon the called subscriber replying. These switch means are arranged so as to control a time switch which is itself arranged so as to cause a supervisory station to be seized when it has remained in operation for a prescribed time. The said switch means may actuate different signals in the supervisory station so that when the latter is seized, the reason becomes immediately apparent. The supervisory device in accordance with the invention thus makes perfect supervision of connections possible in telephone installations having selectors which are set directly by the current impulses dialled by the calling subscriber without the interpolation of storing devices. As the signals which are sent back from the last selector used in making a connection when testing of the desired subscriber's line starts and when the desired subscriber replies may be transmitted over any desired number of selector stages and even over the lines connecting a number of exchanges, the

supervisory devices in accordance with the invention may be used in connection with large automatic telephone networks.

An example of an arrangement in accordance with the invention is illustrated in the accompanying drawings, in which:

Figure 1 shows diagrammatically the switches used for connecting the supervisory station in accordance with the invention to a speech line.

Figure 2 shows the circuits at the calling subscriber's end which are used in making the said connection, and

Figure 3 shows the line selector circuits and the circuits associated with the called subscriber which are used in making the said connection.

The connection of the supervisory station P_1 to the speech line a, b depends upon the condition of four contacts c, k, s and z .

The contact c is controlled by a relay which is energized when speech lines are seized. The contact k is controlled by a switch, the condition of which is dependent upon the receipt of the selecting current impulses from the calling subscriber. The contact s is actuated by a switch which receives a notification signal sent back from the final selector when the latter has been set or when testing of the desired subscriber's line is initiated. The contact z is actuated by a switch which is controlled by a backward signal sent out by the final selector when the called subscriber replies and used, as a rule, for metering purposes. The supervisory station P_1 has a selector PA which can be connected to the speech lines a, b . When the calling subscriber seizes the speech lines, the contact c is closed and the time switch T_h is connected in a circuit running over the contacts c and k and the resistance W_1 . If, at the end of a certain period of time, no selecting current impulses are sent out by the calling subscriber so that the contact k remains closed, the time switch T_h responds and, by means of its contact th closes a circuit for the relay R in the supervisory station. The relay R responds and, by means of its contact r , connects the stepping magnet D_m of the selector PA to an interrupter. The wipers of the selector PA are now stepped until the wiper ca reaches the line determined by the actuated contact c and contact k which is in the normal position. The relay P is then energised and, by means of its contact p , interrupts the stepping of the selector PA . At the same time, the lamp N_1 in the circuit of the relay P is lit up and thus indicates to the supervisory station that the calling subscriber has not yet started to dial. The operator at the super-

visory station can then, as soon as she is connected to the line, ask the calling subscriber what he wants.

If, however, the calling subscriber dials within 5 the predetermined period of time, the contact *k* is thrown and the time switch *Th* is connected in a circuit including the contacts *c*, *k*, *z* and *s* and the resistance *W2*. If now, the backward signal which indicates that testing of the 10 desired subscriber's line has been started, is not received within a certain time, the contact *s* remains unoperated and the time switch *Th* responds and, in a manner similar to that described above, causes the lamp *Ne* to be lit up 15 when the wiper *da* finds the line involved. The operator of the supervisory station is thus informed that the calling subscriber has not properly completed the selecting operation necessary for making the connection, in other words, has 20 not completely set the final selector.

It will now be assumed that the backward signal indicating that testing is in operation has been received within the prescribed period, the contact *s* being thus thrown. The circuit for 25 the time switch is in these circumstances opened and a circuit is closed through the contacts *c*, *k*, *z* and *s* and the resistance *W3*. If now the wanted subscriber does not reply within the prescribed period, the time switch *Th* responds and 30 again causes the supervisory station to be seized. The lamp *Nm* in the circuit of the wiper *cd* is this time lit up so as to indicate to the operator that the called subscriber has not replied. This failure to reply may be due to various reasons. 35 If it is because the calling subscriber has dialled a number corresponding to a non-existent line, the supervisory station is connected automatically without it being necessary, as in certain known arrangements, to connect permanently to 40 the outputs of the line selector special lines leading to an information department. If it is because the called subscriber's line is out of order, the supervisory station is switched in. With the usual arrangements, in such a case, 45 a characteristic signal is given only in the selector racks. If it is because the wanted subscriber is absent or engaged and the calling subscriber is holding on in the hope that the called subscriber will soon be available, it is preferable for 50 an operator to be connected to the calling subscriber by the supervisory device than for the call to be automatically cut off as the calling subscriber can then be informed by the operator and, in future, will refrain from holding on for 55 unnecessarily long periods.

If the calling subscriber replaces his receiver on receiving the automatic signals, the contact *c* is opened and the circuit for the time switch is thus opened. The time switch which is only shown diagrammatically in the drawings can be of any desired form.

Figures 2 and 3 show an example of the principal circuits which can be utilised to cause actuation of the contacts *c*, *k*, *z*, and *s* in the manner and in the circumstances outlined above. Figure 1 is to be considered between Figures 2 and 3 so that the speech lines *a*, *b*, in Figure 2 are connected to the line *a*, *b* in Figure 3 through the 60 lines *a*, *b* in Figure 1. The contacts *c*, *k*, *z*, *s*, in Figure 1 are controlled by the relays *C*, *K*, *Z*, *S* in the call finder illustrated in Figure 2. When the subscriber *TN* (Figure 2) lifts his receiver, a circuit is closed through the winding I of his 65 multi-step relay *T*. On energisation of the wind-

ing I, the relay *T* makes its first step and closes its contacts *t1*, *t2*.

The contact *t2* closes a circuit which runs over the winding I of a relay *N* and the winding II of the relay *AR* of a free call finder *AS*. The 5 relays *N* and *AR* are thus energised. In closing the contact *n1* closes a circuit for the call finder stepping magnet *DAS* which, through the interrupted *RU*, steps the wipers of the call finder until the calling subscriber's contacts are 10 reached. A circuit is then closed for the testing relay *C*. This relay responds and by means of its contact *c1* opens the circuit for the stepping magnet *DAS*. The energising circuit for the relay *C* includes the winding II of the relay *T*. 15 Energisation of this causes the relay *T* to make its second step and open its contacts *t3*, *t4* and *t5*. The relay *AR* is now kept energised through its winding I and the relay *N* through its winding II. The winding II of the relay *AR* is connected through the contacts *n3*, *k2* and *c6* to a 20 source of alternating current *DT* so that a signal is transmitted to the calling subscriber which indicates that he can start to dial.

On energisation of the relay *C*, the contact *c* 25 (Figure 1) is also closed and closes the circuit for the time switch device *Th*.

If the calling subscriber fails to dial within a pre-determined time dependent upon the time switch device *Th*, the supervisory station *Pl* is 30 connected to the speech lines *a*, *b*, in the manner described in connection with Figure 1 and the lamp *Ni* is lit so as to indicate to the operator the fact that the subscriber has not yet dialled. If, however, the subscriber dials within the pre-determined time, the relay *AR* is de-energised at each current impulse. At the first impulse, the contact *ar2* closes a circuit for the relay *K*. This relay is then locked in a circuit closed at its contact *k1* and by opening its contact *k2* disconnects 35 the alternating current source *DT*. The contact *k* (Figure 1) in these circumstances closes a circuit for the time switch device *Th* through the resistance *W2*.

As a result of energisation of the relay *C*, a 45 circuit is closed for the relay *E* at the contact *ar1*. At each de-energisation of the relay *AR*, the following circuit is made:

+, contacts *c4*, *n4*, *z1*, *ar1*, *e1*, *m4*, wire *a* of 50 the speech line, *y3* (Figure 3), relay *RA*, —.

The relay *RA* is energised by each current impulse. Its contact *ra1* closes a circuit for a slow-acting relay *V*, which holds its armature attracted during the reception of a current impulse 55 train. At each current impulse, its contact *ra2* closes a circuit for the lifting magnet *VM* of the line selector *LW*.

As soon as the wipers of the line selector *LW* leave their normal position, a contact *NO* is 60 thrown.

At the end of the first current impulse train, the relay *V* releases slowly. Its contact *v1* closes a circuit for the winding I of slow-acting relay *U*, which responds and by means of its contact *u2* 65 prepares a circuit for the winding I of the relay *ER* while its contact *u3* closes a circuit for the rotary magnet *RM* of the line selector *LW* through the contact *ra2*.

By means of the impulses of the second train, 70 the rotary magnet *RM* is energised. The relay *V* is also again energised so that the contacts *v1* and *u4* maintain the winding I of the relay energised. When, at the end of the second current impulse train, the relay *V* releases its arma- 75

ture, the circuit for the testing relay P is closed at the contacts u_5 and v_2 . If the called subscriber is free, the relay P responds and when the relay U drops closes a circuit for the relay ZR. Should the wanted subscriber be engaged, the testing relay P cannot respond and relay ZR is not energised.

Release of the relay U causes the b-wire of the speech line to be connected to earth over the contact u_6 . The relay M in the call finder AS (Figure 2) is thus energised and its contact m_1 closes a circuit for the relay D. This relay responds so that its contacts d_1 and m_2 short-circuit the winding II of the relay N.

If the called subscriber is engaged so that the relays P and ZR of the line selector (Figure 3) cannot respond, the relay M of the call finder (Figure 2) is continuously energised through the b-wire of the speech line. In these circumstances, the relay N drops and, at its contact n_2 , opens the circuit for the relay C of the call finder AS. Also, its contact n_5 opens the circuit for the relay CR of the line selector (Figure 3) and causes the line selector to be released in the known manner.

If however, the called subscriber is available, the relay ZR opens the circuit of the b-wire at its contact zr_1 shortly after the relay U of the line selector (Figure 3) has dropped. The relay M of the call finder AS then releases again. As the relay D is slow to release, the contact d_1 remains closed for a short time so that the slow-acting relay S responds in a circuit running over the contacts d_1 and m_2 and is locked in a circuit closed by its contact s_1 . A source of alternating current RT is thus connected to the winding II of the relay AR over the contacts n_3 , k_2 , z_4 and s_3 so that the calling subscriber receives a signal which indicates to him that the desired subscriber is being rung. The contact s (Figure 1) controlled by the relay S (Figure 2) then disconnects the time switch Th from the resistance W2 and connects it to the resistance W3.

On its response, the relay ZR of the line selector (Figure 3) is locked in a circuit closed by its contact zr_2 and closes a circuit for the relay Q at its contact zr_3 . The relay Q therefore responds, closes a circuit for the relay L at its contact q_1 and connects the source of ringing current RM to the speech line at its contacts q_2 and q_3 . The selected subscriber is now rung. When he removes his receiver, the winding II of the relay U is energised so that the circuit for the relay L is opened at the contact u_1 . This relay, therefore releases and closes a circuit for the relay Y at its contact 1. The b-wire of the speech line is then earthed by the contacts y_1 and zr_1 so that the relay M of the call finder (Figure 2) again responds. Also, the contact y_2 opens the locking circuit for the relay ZR so that the latter slowly releases and again interrupts the flow of current through the b-wire. When the relay M of the call finder (Figure 2) responds, a circuit is closed for the relay Z at the contact m_3 . This relay is then locked in a circuit closed at the contact z_1 . When the relay M releases, a circuit is closed for the metering magnet ZM at the contacts z_1 , s_2 and m_3 , so that the subscriber's meter is stepped. This circuit is opened when the relay S releases. The contact z (Figure 1), which is actuated by the relay Z, opens the circuit for the time switch device Th and the contact z_4 disconnects the source of alternating current RT so that the

transmission of signals to the calling subscriber is interrupted.

I claim:

1. A telephone installation comprising a calling subscriber's station provided with impulse emitting means, a called subscriber's station, a line between said subscriber's stations provided with impulse receiving means, with automatic selectors, with means for causing the testing of said called subscriber's line and with means operated when said called subscriber removes his receiver, a supervising operator, a time switch for connecting said operator to said line and a plurality of contacts controlled by said three means provided in said line arranged in series in the energisation circuit of said time switch.

2. A telephone installation comprising a calling subscriber's station provided with impulse emitting means, a called subscriber's station, a line between said subscriber's stations provided with impulse receiving means, with automatic selectors, with means for causing testing of said called subscriber's line and with means operated when said called subscriber removes his receiver, a supervising operator, a time switch for connecting said operator to said line, a plurality of contacts arranged in series in the energisation circuit of said time switch and controlled by said three means provided in said line and a plurality of signalling devices adapted to emit signals to said operator, each of said signalling devices being controlled by one of said contacts.

3. A telephone installation comprising at least one unattended and one attended exchange, a calling subscriber's station provided with impulse emitting means, a called subscriber's station, a line between said subscriber's stations provided with impulse receiving means, with automatic selectors, with means for causing testing of said called subscriber's line and with means responsive on said called subscriber removing his receiver, a supervising operator in the attended exchange, a time switch for connecting said operator to said line, a plurality of signalling devices adapted to emit signals to said operator and a plurality of contacts controlled by said impulse receiving means, by said means for causing testing and by said means responsive on said called subscriber removing his receiver and adapted to control said time switch means and said signalling devices.

4. An automatic telephone installation comprising a calling subscriber, a called subscriber, a connecting path between said subscribers comprising impulse receiving means, automatic selectors controlled by said impulse receiving means, means for testing said called subscriber, means operated when said called subscriber removes his receiver, a supervising operator, means for connecting said operator to said connecting path, a plurality of signalling devices adapted to emit different signals to said operator, time switch means operated on seizure of said connecting path by said calling subscriber to cause said operator to be connected to said connecting path and to switch in one of said signalling devices, means operated by said impulse receiving means for controlling said time switch means, means operated by said testing means for controlling said time switch means and means operated when said called subscriber removes his receiver for controlling said time switch means.

5. In an automatic telephone installation the combination of a calling subscriber provided with dialling means, a called subscriber, a connecting

- path connecting said calling subscriber to said called subscriber comprising seizing means actuated upon the seizure of said connecting path by said calling subscriber, impulse receiving means, automatic selectors controlled by said impulse receiving means, means for testing said called subscriber and means actuated upon the response of said called subscriber, time switch means adapted to be made effective by said seizing means, by said automatic selectors, by said testing means and by said means controlled upon the response of said called subscriber, a supervising operator, a plurality of signalling devices adapted to emit different signals to said operator, one of said devices being prepared by said seizing means, another by said automatic selectors and another by said testing means and means controlled by said time switch means for switching in a prepared one of said signalling devices 20 and for connecting said operator to said connecting path.

6. In an automatic telephone installation the combination of a calling subscriber's station provided with dialling means, a called subscriber's station, a connecting path between said sub-

scriber's stations, provided with seizing means operated upon the seizure of said path, with impulse receiving means, with selecting means controlled by said impulse receiving means, with means for testing the called subscriber and with means responsive when said called subscriber removes his receiver, a supervising operator, a plurality of signalling devices situated at said operator's position, time switch means, actuating circuits for said time switch means, a series of contacts in said actuating circuits, one of said contacts being adapted to prepare one of said signalling devices and being controlled by said seizing means, another of said contacts being controlled by said selected means and being adapted to prepare a circuit for another of said signalling devices and another of said contacts being controlled by said testing means and adapted to prepare a circuit for another of said signalling devices, and means controlled by said time switch means for closing a prepared one of said circuits for said signalling devices and for connecting said operator to said connecting path seized by said calling subscriber.

MARTIN HEBEL. 25
